CATALYTIC CONVERSION OF
HYDROCARBONSHerschel D. Radford, Columbia, Mo., assignor to
Pan American Refining Corporation, Texas
City, Tex., a corporation of Delaware

Application July 12, 1947, Serial No. 760,577

5 Claims. (Cl. 196—52)

1

This invention relates to a process of converting hydrocarbon oils such as gas oil, reduced crude oil, and other heavy petroleum stocks into gasoline. More particularly the invention relates to an improved combination of processes wherein a more extensive conversion of the heavy oil into gasoline is obtained by the co-action of hydrofluoric acid and argillaceous catalysts acting separately in successive stages.

One object of the invention is to improve the operation of the catalytic cracking process employing refractory solid argillaceous and refractory oxide catalysts by refining the heavy oil charging stock employed therein, thereby increasing catalyst life and extent of conversion and improving product distribution. Another object of the invention is to eliminate from the recycle stock in an oxide catalyst cracking system carbon-producing ingredients such as aromatics and naphthenes without losing the potential gasoline-producing capacity derivable from these constituents. Yet another object of the invention is to eliminate combined fluorine from HF conversion gas oil and simultaneously activate oxide conversion catalyst therewith. Other objects of the invention will be apparent from the following description thereof.

The invention is illustrated by a drawing which shows diagrammatically an apparatus suitable for carrying out the process.

In the catalytic cracking of heavy oils such as gas oil and reduced crude oil, the heated oil which may or may not be vaporized is charged to the catalyst and contacted therewith for a short time at temperatures of the order of 850 to 1000° F. Catalysts for this reaction are usually natural clays, preferably acid-treated clays of the montmorillonite type, or metal oxides, active silica, alumina, boron oxide, zirconium oxide, magnesia, or mixtures thereof. One of the best known synthetic catalysts for the reaction is silica gel promoted with about 10 to 25 per cent of aluminum oxide or magnesium oxide while the most commonly used natural catalyst is Super Filtral, an acid-treated montmorillonite clay. These catalysts, hereinafter referred to as "oxide catalysts," may be employed in the form of porous beds, either fixed or moving beds thru which the hydrocarbon vapors are passed, or they may be employed in the form of powders mixed with the hydrocarbon vapors in the so-called "fluid" cracking process.

In either case a substantial part of the hydrocarbon material is converted to non-volatile carbonaceous deposits commonly termed "coke"

which forms on the surface of the catalyst. This coke must be removed from the catalyst from time to time by burning in order to maintain catalyst activity. The amount of potential fuel lost in this way is a very considerable item in the cost of operating the process, for a number of reasons. First, the actual inventory loss on a weight basis amounts to about 5% or more depending upon the character of the stock employed. When charging reduced crude oil the loss is substantially greater, e. g. 7 to 10 per cent. In addition to the actual weight loss, there is the cost of supplying to the process the large volume of air required for effective combustion of the coke. Another important cost is the increased cost of the apparatus required for dissipating the heat evolved in the combustion and for handling the large volume of gases in the combustion-regeneration. It is characteristic of aromatic-type charging stocks that more coke is produced by their use and this is also true to a lesser extent of the naphthenic stocks, whereas the paraffinic-type charging stocks produce a minimum amount of coke and are therefore preferred for the oxide catalyst cracking process. Even where paraffinic stocks are available, however, it has been found that the so-called cycle stock produced in the process is of highly aromatic or naphthenic character and is generally unsuitable for recycling to the catalytic cracking operation because of its high coke-forming tendency which increases the cost of the conversion operation disproportionately, resulting in lower net gasoline recovery and lower rate of conversion of this catalytic cycle stock to gasoline.

For the purpose of this invention, I class as aromatic cracking stocks those oils having a Watson characterization factor (K) below about 11.75, and as paraffinic stocks those having a K value above about 11.75. The characterization factor,

$$K = \frac{(T_b)^{1/3}}{s}$$

where T_b =molal average boiling point, ° Rankine, and s =sp. gr. at 60/60° F., is described in a publication by Watson and Nelson—Ind. & Eng. Chem., vol. 25 (1933), page 880.

According to my invention, I eliminate the recycle fractions boiling higher than gasoline obtained from the solid oxide catalyst cracking step and subject these fractions to conversion with hydrofluoric acid catalyst at considerably lower temperatures than those employed with the refractory argillaceous oxide catalysts. The hy-

drofluoric acid treatment effects an extensive reportionment of the hydrogen, producing on the one hand, highly condensed aromatic hydrocarbons or asphaltenes soluble in liquid HF, and on the other hand, paraffinic-type hydrocarbons insoluble in liquid HF. The latter hydrocarbons, after removal of gasoline, are then returned according to my process to the refractory oxide catalyst conversion system where they are easily converted with low coke production into gasoline of high knock rating. The highly aromatic or asphaltic material separated from solution in the HF can be liquefied at moderately elevated temperatures and used efficiently as a constituent of liquid fuels or for other purposes where such material is adapted as in paving, coating, plasticizing, etc. Thus the combination of refractory solid catalyst in one stage with hydrofluoric acid catalyst in another stage results in maximum production of gasoline and minimum losses by way of coke formation. The production of permanent gases such as methane and ethane is also reduced substantially.

Referring to the drawing, the paraffinic feed stock, for example Pennsylvania or Mid-Continent gas oil, is charged by line 10 to heater 11 wherein it is heated to the desired cracking temperature or simply preheated, for example to 500°-900° F. The charge passes by line 12 thru catalyst eductor 13 and thence by line 14 to reactor 15. Powdered solid catalyst from standpipe 16 is introduced into the vapors at 13, usually at the ratio of about 2 to 10 pounds of catalyst per pound of hydrocarbons, altho catalyst: oil ratios as high as 15 to 20 may be employed. In reactor 15 a fluidized dense suspension of catalyst is maintained with a density of the order of 15 to 35 pounds per cubic foot, the density being determined by the character of the catalyst, its particle size, and by the velocity of the upflowing vapors in the reactor. A suitable velocity is about 1 to 3 feet per second. The vapors separate from the fluidized body of catalyst in the reactor and are withdrawn thru cyclone separator 17 and vapor line 18 leading to fractionator 19. The catalyst overthrows into downcomer 20 leading to stripper 21 supplied by a current of steam or other stripping gas by line 22 for the removal of adhering volatilizable hydrocarbons. The stripping gas and vapors pass by line 23 into the main products stream in the top of the reactor 15. The catalyst flows from the stripper by line 24 and is conducted by line 25 to a low point in regenerator 26. Air or other carrier gas is introduced by line 27 and serves to distribute the catalyst evenly in the regenerator, where a dense phase is maintained by controlling the upflow gas velocity at about 1 to 3 feet per second. Additional air for combustion of coke on the catalyst can be supplied by line 28. Spent regeneration gases escape from the regenerator by cyclone separator 29 and line 30, while the regenerated catalyst returns to the reactor by standpipe 16. Cooling of the regenerator by external cycling of catalyst thru a cooler or by other means is now shown.

In fractionator 19, the products are separated into gasoline, light gas oil, heavy gas oil, and slurry oil containing fine catalyst carryover from 15. The gasoline vapors and uncondensable gases are conducted by line 31 to condenser 32 and thence to receiver 33, whence uncondensed gases including methane, ethane and propane are discharged by line 34 and valve 35. Light gas oil is withdrawn by line 36 and may be recycled to the catalytic cracking step by pump 37. Heavy gas oil is

conducted by lines 38 and 39 to be treated with hydrofluoric acid as hereinafter described. If desired, part or all of the light gas oil may also be transferred by line 36 into line 39 for treatment with HF. The slurry oil is withdrawn by line 40 and returned to the oxide catalyst system in the feed stock or through the eductor 13 by suitable connections, not shown.

The so-called cycle gas oil from the oxide catalyst system is discharged by line 39 into HF reactor 41 which is illustrated equipped with mechanical agitator 42 for obtaining satisfactory contact between HF and hydrocarbon phases altho other means of obtaining contact may be provided. The temperature in reactor 41 is maintained above about 250° F., by internal heating coils, not shown, or by heating the feed stock above the reaction temperature by conventional heating means. A temperature of the order of 300 to 450° F. is effective for converting the hydrocarbons therein. It is also preferred to maintain a substantial pressure, preferably a pressure somewhat above the vapor pressure of liquid HF at the temperature employed. Liquid HF is supplied to the reactor from tank 43 by line 44.

At the preferred reaction temperature of about 350 to 425° F. the HF phase is usually lighter than the hydrocarbon phase and passes to the top of reactor 41 whence it is withdrawn by line 45 to settler 46 and thence by line 47 to cooler 48 and separator 49, altho where a highly aromatic feed stock is charged to the reactor the hydrocarbon phase may be lighter and become the upper layer. In normal operation, any hydrocarbon phase entrained in the HF phase in line 45 is returned to the reactor 41 by line 50. On cooling in 48 a phase separation occurs and the HF phase now collects on the bottom of separator 49 whence it is withdrawn by line 51 leading to pressure-reducing valve 52 and stripper 53 where the HF is driven off by heating and the hydrocarbon tar fraction, liquid when hot, is withdrawn by valved line 54. The recovered HF is conducted by line 55, condensed in condenser 56, separated from light hydrocarbon oil in 57, and returned by pump 58 and line 59 to reactor 41. Light liquid hydrocarbon, usually unsaturated olefinic stock which separates in 57, is withdrawn via line 60.

Liquid hydrocarbons separated in 49 as an upper layer are conducted by line 61 to fractionator 62 where gasoline is separated and withdrawn by line 63 and higher boiling fractions are recycled to the reactor by line 64. Uncondensed gases from separator 49 are conducted by line 65 to compressor 66 where the pressure is restored to that maintained in reactor 41. A portion of the gases including most of the HF vapor contained therein condenses and is separated by separator 67, the liquid returning by line 68 to reactor 41. Uncondensable gases including methane are discharged from the system by line 69.

From the base of reactor 41 the hydrocarbon phase is withdrawn by line 70 leading to separator 71 from which any entrained liquid HF is returned by line 72 to the reactor. The hydrocarbon product is thence conducted by line 73 thru cooler 74 to separator 75 wherein a separation into a hydrocarbon and an HF phase occurs at the lower temperature maintained therein, e. g. 75 to 150° F. The separated HF passes by line 76 back to reactor 41.

The hydrocarbon upper layer in separator 75 is withdrawn by line 77 thru valve 78 to fractionator 79 where a gasoline fraction is distilled off and withdrawn by line 80. Gasoline from

line 63 may be admixed therewith if desired. The gases lighter than gasoline, e. g. methane, propane and butane, pass by line 81 to stabilizer 82 wherein any HF and condensable hydrocarbons, particularly butane, are recovered and either returned by line 83 and pump 84 to reactor 41, or recovered as a separate stream. Uncondensable gases primarily propane with some methane and any ethane produced in the operation are removed from the system by line 10 85.

Paraffinic hydrocarbon products boiling above the boiling point of gasoline are collected in the base of fractionator 79 and conducted by line 86 and pump 87 to heater 11 after which these hydrocarbons are subjected to further cracking with oxide catalyst as hereinbefore described. Fluorine combined in this stock, usually to the extent of 0.01 to 0.1 per cent, is eliminated by reaction with the oxide catalyst to form a 20 metal fluoride having a promoting action on that catalyst.

If desired, I may charge to the HF conversion reactor directly a naphthenic or aromatic feed stock supplied by line 88. For this purpose gas oil or residuum from naphthenic crudes are satisfactory, examples of which are gas oil or residuum from Winkler County, Texas, crude, Slaughter crude from West Texas, Rangely crude or California crudes of high aromatic content such as that from Elk Hills. Heavy refractory stocks from thermal cracking processes may also be added directly to the HF conversion reaction. The process may be supplied by feed stock from either 10 and 88 simultaneously or from either source alone if desired. Where the process is charged with a reduced crude oil it is preferred to feed it to the HF stage thru line 88 and feed the oxide catalyst stage with the paraffinic gas oil produced in the HF conversion operation thru transfer line 86. As a general rule, I can charge the HF conversion stage with a stock having a K value of about 10 to 11.5 while the oxide catalyst stage is charged with a stock having a K value of about 11.75 to 12.75. Stocks containing substantial amounts, e. g. 0.1 to 2 per cent of certain nitrogen bases, generally of the pyridine and quinoline series, have an undesirable deactivating effect on the oxide catalyst in the solid oxide conversion stage and I prefer to charge such stocks directly to the HF stage by line 88 where the bases are quantitatively removed by absorption in the HF.

The hydrocarbon gases produced in the oxide catalyst stage of the process and eliminated by line 35 may, if desired, be conducted by line 89 to the HF catalyst stage thru the same vapor system employed for handling light hydrocarbons from separator 49. It is important, however, to avoid transferring water vapors with such gases and it may be desirable to subject them to drying by means not shown. If there is a substantial amount of dissolved water in the stocks flowing thru lines 36 and 38 into reactor 41 by line 39, it may also be necessary to employ a dryer for these stocks to prevent excessive H₂O contamination of the HF catalyst in reactor 41. In general, it is desirable to maintain the HF in reactor 41 near anhydrous condition, a concentration of 95 to 99 per cent being desirable based on the combined weight of HF and H₂O present.

In the operation of the HF conversion stage, the amount of the HF phase withdrawn by line 45 is controlled to maintain a substantial amount

of HF-soluble hydrocarbon in reactor 41, as it has been found that the rate of reaction is substantially increased by an amount of HF-soluble or tar phase within an optimum range of concentration. Thus it is generally desirable to have present in the reactor about 15 to 50 per cent of HF-soluble hydrocarbons based on the combined weight of these hydrocarbons and the HF present.

In a typical operation in which a West Texas gas oil was charged directly to the HF conversion operation, a heavy product fraction was obtained having improved conversion characteristics when contacted with catalyst in the refractory oxide catalyst reactor. A comparison of these stocks shows the following relations:

	Original Gas Oil	Heavy HF Conver- sion Product Suitable for Oxide Cata- lyst Con- version
Gravity A. P. I degrees.....	39	43.2
50% ASTM degrees F.....	515	583
Characterization Factor (Watson).....	11.75	12.1

Inspection of these data shows that the gas oil charge to the HF conversion unit was substantially improved in its characteristics for oxide catalyst cracking while at the same time a high quality gasoline distillate was obtained from the HF treatment. The amount of the gasoline products in the HF treatment depends partly on the character of the charging stock and partly on the conditions employed in HF treating. The amount of gasoline may be equal to the weight of product gas oil produced or two to three times the weight of the product gas oil. In general, it is not possible to operate under such conditions that only gas oil is produced in the HF conversion stage to the exclusion of gasoline production.

Another indication of the powerful hydrogen reportioning action of the HF-hydrocarbon complex employed in the HF conversion stage—a residuum having an A. P. I. gravity of 21.7 was charged thereto and the resulting tar eliminated at 54 was obtained with an A. P. I. gravity of less than 10, i. e. a product of such low hydrogen content that it is heavier than water. In general, it is desirable to operate the process to produce an HF tar product having an A. P. I. gravity less than that of water, usually within the range of 5 to 10° A. P. I.

In a typical operation, there was charged to the HF conversion stage a naphthenic gas oil of 31° A. P. I. gravity. The HF contacting reactor was maintained at 400° F. and at a pressure of about 900 p. s. i. The ratio of HF to oil charged was 3.1, the rate of charge being 0.83 volume of oil per hour per volume of liquid HF in the reactor corresponding to a contact time in the reactor of 7.2 minutes, assuming the specific gravity of HF at 400° F. to be 0.3. The product recovery was 97.6 per cent based on charge. The following products were obtained:

	Per cent by weight
Dry gas	0.4
Excess isobutane	3.2
Gasoline, 10 lb. R. V. P.	27.0
Gas oil insoluble in HF	39.6
Gas oil soluble in HF	6.0
Tar boiling above 650° F.	23.8
Total conversion	54.4

The gasoline had an A. S. T. M. motor octane number of 75.3. The HF-insoluble gas oil was characterized by an A. P. I. gravity of 30.6 and was ideally suited for conversion into gasoline by contacting with refractory oxide catalysts as hereinabove described for the preparation of motor fuel of 78-82 octane number (A. S. T. M.).

Having thus described my invention what I claim is:

1. The process of converting hydrocarbon oils which comprises contacting a heavy paraffinic hydrocarbon charging stock having a characterization factor above 11.75 with a refractory oxide catalyst at conversion temperature in an oxide catalyst conversion operation, recovering therefrom a gasoline fraction and an aromatic heavier-than-gasoline fraction, contacting a heavy aromatic charging stock having a characterization factor below 11.75 with liquid hydrofluoric acid at conversion temperature of about 300 to 450° F. in an HF conversion operation whereby it is substantially converted into gasoline and a paraffinic heavier-than-gasoline fraction having a characterization factor above 11.75 substantially less aromatic than said aromatic charging stock, charging said heavy paraffinic fraction produced in said HF conversion operation to said oxide catalyst conversion operation and charging said heavier-than-gasoline aromatic fraction from the first-named conversion operation directly to said HF conversion operation.

2. The process of claim 1 wherein all the paraffinic stock charged to said oxide conversion operation comprises the heavy paraffinic fraction produced in said HF conversion operation.

3. The process of claim 1 wherein all the aromatic charging stock supplied to said HF conversion operation comprises the heavy aromatic fraction of the products recovered from said oxide catalyst conversion operation.

4. The process of converting hydrocarbon oils

which comprises converting a heavy aromatic-type hydrocarbon oil having a characterization factor below 11.75 by contacting with liquid HF at a temperature of about 300 to 450° F. in a HF conversion operation, separating the products into gasoline, gas, tar and paraffinic-type gas oil having a characterization factor above 11.75, converting heavy paraffinic hydrocarbons by contacting with a refractory oxide catalyst at conversion temperature in an oxide catalyst conversion operation and separating the products thereof into gas, gasoline and a heavy aromatic gas oil fraction having a characterization factor below 11.75, charging said heavy aromatic gas oil fraction to said HF conversion operation, charging said paraffinic-type gas oil fraction to said oxide conversion operation and charging hydrocarbon gas from both HF and oxide conversion operations to said HF conversion operation.

10 5. The process of claim 4 wherein an HF-soluble hydrocarbon phase is retained in the HF conversion zone for a period of time sufficient to produce a product tar fraction having an A. P. I. gravity of about 5 to 10 and a melting point, 20 A. S. T. M., above about 200° C.
